United States Patent

Des. 242,133

Patented Nov. 2, 1976

242,133

SMOKE ALARM OR SIMILAR ARTICLE

George Henry Fitzsimonds, Bridgeport, Conn., assignor to
General Electric Company

Filed Nov. 10, 1975, Ser. No. 630,205

Term of patent 14 years

Int. Cl. D10—05

U.S. Cl. D10—106

FIG. 1.

FIG. 2.

FIG. 3.

FIG. 4.

FIG. 5.

FIG. 6.

FIG. 7.

FIG. 1 is a bottom perspective view of a smoke alarm or similar article as it appears when mounted on a ceiling or the like;

FIG. 2 is a bottom plan view thereof;

FIG. 3 is a top plan view thereof;

FIG. 4 is a right side elevation view of the smoke alarm or similar article shown by FIG. 2;

FIG. 5 is a front elevation view thereof, the back side being substantially a mirror image thereof;

FIG. 6 is a left side elevational view thereof; and

FIG. 7 is a view similar to FIG. 2 in which a movable flag element is shown in its displayed position with the broken line disclosure being for illustrative purposes only.

I claim:

The ornamental design for a smoke alarm or similar article, as shown and described.
